HYDRAULIC CONTROL VALVE

Edward Clifford Dudley, Fresno, Calif.

Application April 28, 1937, Serial No. 139,370

1 Claim. (Cl. 251—108)

This invention relates generally to a hydraulic control valve and in particular relates to an improved hydraulic control valve, of the four-way type, for use in connection with double acting hydraulic control cylinders as now commonly used in connection with tractor drawn earth working and moving implements such as carrier scrapers, etc., the valve being interposed in the conduits between the constant pressure pump on the tractor and the control cylinder on the implements.

The principal object of the present invention is to provide a novel porting arrangement in a four-way control valve of the plug type. The porting is so disposed that when the valve is in a central or neutral position, the high pressure oil from the pump will by-pass back to the oil reservoir on the tractor and when the valve is turned in one direction or the other to feed oil under pressure to one side of the double acting control cylinder on the implement, the oil from the other side of the cylinder is by-passed through the valve and back to the oil reservoir.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawing similar characters of reference indicate corresponding parts in the several views:

35 Figure 1 is an elevation of my improved hydraulic control valve.

Figure 2 is a sectional elevation on line 2—2 of Fig. 1.

40 Figure 3 is a cross section taken on line 3—3 of Fig. 2, and illustrates the valve in a neutral or by-passing position.

Figure 4 is a similar view but illustrating the valve in an operative position.

Referring now more particularly to the characters of reference on the drawing, the device comprises a valve shell 1 bored from one end to receive a tapered plug 2; the plug when disposed in the bore terminating short of the bottom thereof to form a pocket as shown at 3. An axial stem 4 projects from the enlarged end of the plug 2 some distance beyond the adjacent end of the valve shell; a control handle H projecting radially from the outer end of the stem. A head 5 is threaded into the initially open end 55 of the shell and forms a journal for stem 4.

The head 5 is provided with an enlarged bore 6 below its stem journaling portion and open at its inner end and thus in communication with a chamber 7 formed between the inner face of the head and adjacent end of plug 2. An oil seal 8, 5 of suitable type, is disposed about the stem and in the bottom of bore 6. A compression spring 9 is disposed about the stem between the oil seal 8 and the adjacent end of plug 2; said spring normally being under compression and 10 urging the plug into the tapered bore. If desired, a washer 10 may be disposed between the oil seal and spring whereby to increase the compression of spring 9 for the purpose hereinafter described. 15

The shell 1 is provided with two oppositely disposed, radial ports indicated at 11 and 12 respectively. Another radial port 13 is disposed centrally between the ports 11 and 12 while a fourth port 14 is formed in the shell axially relative to the plug and communicates with the bottom of the tapered bore which forms pocket 3. The tapped radial ports 11 and 12 are the supply ports from which the conduits (not shown) lead to the double acting hydraulic control cylinder; the radial port 13 is the by-pass port which is connected to the oil supply reservoir; and the axial port 14 is the high pressure feed port adapted to be connected to the pump. 20 25 30

The plug 2 is formed with an L-shaped passage 15 which is open at one end to the small end of the plug and open at the other end through the side wall of the plug in the plane of the radial ports. The plug is also formed with a pair of outwardly facing, opposed parallel grooves 16 and 35 17 respectively cut transversely therein; said grooves also being disposed in the plane of the radial ports and at right angles to the axis of ports 11 and 12 when passage 15 and port 13 are in full register as shown in Fig. 3. A bleed opening 18 extends longitudinally through the plug to one side of passage 15; said bleed opening affording communication between pocket 3 and chamber 7. 40

In use my improved hydraulic control valve is 45 mounted in any suitable manner on the tractor, and connected between the pump and double acting hydraulic control cylinder in the manner hereinafter described.

When the valve is in a neutral or central position as shown in Fig. 3, the L-shaped passage 15 in the plug is in register with radial port 13 and axial port 14 thus allowing of unrestricted by-passing of oil from the constant pressure pump back to the reservoir. However when the plug is 50 55

turned in one direction or the other a predetermined distance either radial port 11 or 12 is placed in communication with the passage 15 thus feeding oil under pressure to one side of the double acting hydraulic control cylinder on the drawn implement. At the same time one of the grooves 16 or 17 will be brought into register between radial by-pass port 13 and the other radial supply port relieving the pressure on the other side of 10 the control cylinder. Figure 4 of the drawing illustrates the position of the plug when oil is being supplied to port 11 and by-passed from port 12. To control the operation of the double acting control cylinder, it is therefore only necessary to 15 swing the handle H of the valve to one side or the other of its neutral or central position.

From the foregoing description it will be readily seen that I have produced such a device as substantially fulfills the objects of the invention as 20 set forth herein.

While this specification sets forth in detail the present and preferred construction of the device, still in practice such deviations from such detail may be resorted to as do not form a departure 25 from the spirit of the invention, as defined by the appended claim.

Having thus described my invention, what I claim as new and useful and desire to secure by Letters Patent is:

In a hydraulic control valve including a shell and a rotatable plug disposed therein, a radial by-pass port in the shell, a pair of feed ports in the shell, the radial by-pass port being disposed centrally between said feed ports and in the same plane transversely of the valve, and an axial supply port in the shell, the plug having a passage 10 therein extending from the end adjacent the axial supply port to an opening in the side of the plug in the same plane as said by-pass port and feed ports, the plug also having a pair of transverse grooves cut in the face thereof in the plane of 15 said opening and between which the opening is disposed; the ports in the shell and the opening and grooves in the plug being arranged so that when the plug opening is in register with the radial by-pass port, the feed ports will be closed, 20 and when the plug is rotated a predetermined distance in one direction the plug opening will register with one feed port and one groove will establish communication between the other feed port and by-pass port.

EDWARD CLIFFORD DUDLEY
